UNITED STATES PATENT OFFICE

BRUNO STANGE, OF WEST NEW YORK, NEW JERSEY, ASSIGNOR TO FRANK ROSEN,
TRADING AS VICTORY LAMP COMPANY, OF PHILADELPHIA, PENNSYLVANIA

DESIGN FOR A LIGHTING FIXTURE

Application filed June 10, 1931. Serial No. 40,150. Term of patent 3½ years.

To all whom it may concern:

Be it known that I, BRUNO STANGE, a citizen of the Republic of Germany, and a resident of West New York, Hudson County, and State of New Jersey, have invented a new, original, and ornamental Design for a Lighting Fixture, of which the following is a specification, reference being had to the drawings, forming a part thereof.

Figure 2 is an inverted plan view of the lighting fixture, the parts shown in full line outline in each of these figures being ornamented in the same manner as the parts more fully illustrated.

I claim:

The ornamental design for a lighting fixture substantially as shown and described.

BRUNO STANGE.
